PORTABLE PNEUMATICALLY POWERED HYDRAULIC PUMP

Marcel P. D'Haem, New Hartford, and W. Leslie Jones,
Frankfort, N.Y., assignors to Chicago Pneumatic Tool
Company, New York, N.Y.

Filed June 2, 1971, Ser. No. 149,415

Term of patent 14 years

Int. Cl. D15—02

U.S. Cl. D65—1

FIG. 1

FIG. 2

FIG.3

FIG. 4

FIG. 5

FIG. 7

FIG. 6

FIG. 1 is a top plan view of a portable pneumatically powered hydraulic pump embodying our new design;

FIGS. 2 and 3 are elevational views of opposite sides thereof;

FIG. 4 is a left end elevational view thereof;

FIG. 5 is a right end elevational view thereof;

FIG. 6 is a bottom plan view thereof; and

FIG. 7 is a fragmentary cross sectional view taken on line 7-7 of FIG. 6.

We claim:

The ornamental design for a portable pneumatically powered hydraulic pump, as shown.
